UNITED STATES PATENT OFFICE.

PERLEY R. GLASS, OF WAYLAND, MASSACHUSETTS, ASSIGNOR TO UNITED SHOE MACHINE CORPORATION, OF PATERSON, NEW JERSEY, A CORPORATION OF NEW JERSEY.

FASTENER-SETTING MACHINE.

Application filed May 17, 1922. Serial No. 561,667.

To all whom it may concern:

Be it known that I, PERLEY R. GLASS, a citizen of the United States, residing at Wayland, in the county of Middlesex and 5 State of Massachusetts, have invented certain Improvements in Fastener-Setting Machines, of which the following description, in connection with the accompanying drawings, is a specification, like reference characters 10 on the drawings indicating like parts in the several figures.

This invention relates to fastener-setting machines and more particularly to fastener-supplying mechanisms with which such machines 15 are provided. In some respects the invention is more particularly related to machines of the duplex type but in other respects it is related to fastener-setting machines of various types including those of 20 the duplex type. For purposes of illustration the invention is shown by the accompanying drawings as embodied in a duplex eyeleting machine, in which connection some of the novel features are of special utility, 25 but in regard to those features of general utility neither the duplex aspect nor the particular type of fastener is to be regarded as limiting the invention.

So far as the invention relates particularly to duplex eyeleting machines a brief discussion of prior constructions will facilitate the description that follows. Duplex eyeleting machines designed to set eyelets simultaneously in the right and left quarters 35 of a shoe upper are so organized that eyelets for one quarter are inserted in one direction while those for the other quarter are inserted in the opposite direction. The inserting tools are therefore oppositely disposed in 40 their relation to each other, and the eyelets supplied to one of them must be reversed end for end relatively to those supplied to the other. In the majority of such machines the eyelets for both quarters are supplied by 45 a single hopper from which they are conducted by raceways. In such cases the eyelets for both raceways have stood in the same position at the moment of entering the raceways, that is to say, their flanges have rested 50 on the bottom of the hopper and their smaller ends have been uppermost. This has necessitated forming one of the raceways

with a bend or twist to reverse the position of the eyelets therein so that, on reaching the delivery ends of the raceways, those in 55 one raceway will be inverted relatively to those in the other raceway. Such a bend or twist in one of the raceways has several disadvantages, among which are the following, viz: it increases the cost of manufacture, it 60 militates against the passage of the eyelets therethrough, and it requires additional space which, in many cases, involves the sacrifice of desirable features of machine organization merely to avoid interference by 65 such raceway.

To avoid the objectionable features of the construction outlined in the last preceding paragraph it has been proposed to provide a duplex machine with two hoppers from one 70 of which the eyelets are conducted while standing in one position and from the other of which they are conducted while standing in a reversed position.

In view of the requirements, problems and difficulties hereinbefore set forth an object of this invention is to provide a duplex raceway (two companion raceways in duplex relation) in combination with a single hopper for supplying eyelets to both sections of 75 such raceway in such manner that the eyelets supplied to one will be oppositely disposed relatively to those supplied to the other at the moment of entering into the receiving ends of the raceway sections, eliminating the bend or twist that has heretofore been necessary to reverse the positions of the eyelets of one series before they reach the inserting tools, and at the same time providing a more compact and less expensive 80 organization than the two hopper type. The illustrated construction not only solves the problem so far as the raceways are concerned but provides an improved hopper 85 having the novel features hereinafter referred to.

Another object of the invention is to provide improved transmission mechanism for operating the feeder by which fasteners are 100 fed from a hopper into one or more raceways, as the case may be. Generally speaking, automatic fastener-inserting machines are operated at speeds ranging from 250 to 500 cycles per minute, some being operated

at still greater speeds. In such machines the operating shaft is usually provided with a pulley to drive a belt for transmitting rotation to the feeder in the hopper, but since a 5 very slow speed of rotation on the part of the feeder is usually necessary, designers of such machines have been constantly confronted with the problem of reducing the speed of transmission to avoid over-speed 10 ing the feeder. Even when the driving pulley for such a belt is reduced to the smallest possible diameter and the receiving pulley is enlarged to the greatest possible diameter consistent with the proportions of the 15 machine, it is difficult if not impossible to obtain a sufficient reduction to avoid overspeeding the feeder. Various forms of intermediate speed-reducing mechanism have been proposed, but they are costly from the 20 manufacturing standpoint and cumbersome from the designing standpoint.

Accordingly a feature of this invention consists in an improved form of speed-reducing mechanism adapted to fulfill the requirements above mentioned.

Still another object of the invention is to provide improved transmission mechanism for operating the feeding device either continuously or intermittently, as may be desired. Automatic fastener-inserting machines are usually provided with a disconnectible clutch for driving the operating shaft. The receiving pulley of such a clutch rotates continuously but the operating shaft 30 of the machine turns only when the clutch is connected. If the pulley for driving the feeder belt is fastened to the operating shaft 35 it will operate the feeder only when the operating shaft is in motion, and in some 40 machines the periods of activity of the feeder under such conditions are not sufficient to maintain a full supply of fasteners in the raceway or raceways. On the other hand, if the pulley for driving the feeder belt rotates continuously there will be times 45 when the feeder will tend to over-charge the raceway or raceways, as when the use of the machine is interrupted for protracted periods. At such times the feeder will, by 50 its continuous agitating action, tumble the fasteners about in the hopper all to no purpose, not only wearing out the transmission mechanism and the feeder unnecessarily, but also marring the finish of fasteners 55 such as japanned eyelets and lacing-hooks, fast color eyelets and lacing hooks, and other types of fasteners susceptible to injury by rubbing and scratching.

Accordingly a feature of the invention 60 consists in the combination with an operating shaft and a disconnectible, continuously rotating element for driving such shaft, of disconnectible transmission means arranged to transmit rotation of the fastener feeder 65 either directly from the continuously ro-

tating member or from the disconnectible operating shaft associated therewith, said transmission means being controllable at will so that its connection may be shifted as desired from the continuously rotating element to the intermittently driven element 70 and vice versa.

Referring to the drawings,

Fig. 1 is a perspective view of a portion of a duplex eyeleting machine embodying 75 the several features of this invention;

Fig. 2 is a plan view of the upper portion of the raceway structure and includes the hopper in section;

Fig. 3 is a sectional view through the 80 hopper and transmission gearing for operating the feeder in the hopper, the plane of the section being indicated by the line 3-3 of Fig. 2;

Fig. 4 is a section through the structure 85 intersected by line 4-4 of Fig. 2;

Fig. 5 is a section through the structure intersected by line 5-5 of Fig. 2;

Fig. 6 is a section through the clutch mechanism; and 90

Fig. 7 is an elevation of the setting tools in duplex relation about to take eyelets from the raceways.

According to the usual duplex construction the fastener-inserting tools 10 and 11 95 are arranged in alinement with each other and are movable toward and from each other. They are carried by plungers 12 and 13 respectively and are provided with spindles 14 and 15 of well-known construction and arrangement for picking eyelets from the raceways.

The raceway for the tool 10 is indicated at 16 and that for the tool 11 at 17. Eyelets are supplied to the upper ends of the raceways by a hopper 18 the bottom piece 19 of which is flat and inclined to cause the eyelets to gravitate. A rotary feeder 20 of well-known construction is arranged in the hopper, is seated on the bottom piece 19 110 and turns in the direction indicated by an arrow in Fig. 2. The two raceways and the hopper are fixed relatively to each other to form a detachable unit and are carried by a swinging frame 21 arranged between fixtures 22 such as bosses formed on the main frame 23 of the machine and connected to said bosses by a pivot member 24. The hopper is cylindric and is preferably arranged so that its axis coincides with that of the pivot member 24. Suitable mechanism, shown in my copending application Serial No. 469,666, filed May 14, 1921, imparts oscillatory movement to the pivoted frame 21 115 for the purpose of swinging the delivery ends of the raceways to and from registration with the inserting tools, said mechanism being operable by the cam shaft 25 of the machine. The axis of the inserting tools 120 is preferably inclined to facilitate manipula-

tion.

Accordingly a feature of the invention 125 consists in the combination with an operating shaft and a disconnectible, continuously rotating element for driving such shaft, of disconnectible transmission means arranged to transmit rotation of the fastener feeder 130 either directly from the continuously ro-

tion and observation of the work, and the axis of the raceway structure is preferably inclined in nearly, if not quite, the same way.

5 As shown by Fig. 7, the position of the eyelet about to be taken by the upper inserting tool is the reverse of that about to be taken by the lower tool, that is to say, the flange of the upper eyelet is at the top 10 while that of the lower eyelet is at the bottom. The raceways are so constructed as to conduct the eyelets in this relation from the hopper to the inserting tools, such relation being established before the eyelets 15 leave the hopper and therefore avoiding the necessity of introducing a bend or twist into one of the raceways, as formerly, to invert the eyelets of one series relatively to those of the other. This involves certain 20 novel features of construction in the hopper which will now be described.

As shown by Fig. 2 the peripheral wall 25 of the hopper has a series of outlet ports 26 each shaped to conform to the periphery of an eyelet and each arranged to emit only those eyelets that stand with their flanges on the bottom plate 19. These eyelets pass through the ports 26, are urged through the ports 26 by tufts 30 of bristles comprised 30 in the construction of the feeder 20, and gravitate from said ports into the raceway 17 by which they are maintained so that their unclenched barrel portions extend upwardly from the flanges which slide on the 35 bottom of the raceway.

The raceway 16, however, is supplied with eyelets whose unclenched barrel portions extend downwardly from the flanges. For this purpose the bottom plate 19 of the hopper is provided with a slot 27 into which the depending barrel portions may drop so 40 that the flanges at the top of such eyelets may overlap the edges of said slot and bear on the bottom plate. This slot conducts the 45 suspended eyelets through an outlet port 28 in the peripheral wall of the hopper and leads the eyelets into the raceway 16 which constitutes a continuation of the slot 27. Although these eyelets naturally tend to 50 pass through the outlet port 28 by gravitation, owing to the inclination of the bottom plate 19, they are urged forward by the tufts of bristles with which the rotary feeder 20 is provided. Furthermore, the upper 55 portion of the slot 27 is preferably curved in concentric relation to the axis of the feeder and is of considerable length so that an adequate supply of eyelets may find their way into the slot within the confines of 60 the hopper.

The raceways may have slight bends to 65 avoid interference with other elements of the machine organization, but whether this is or is not necessary, no bend or twist is required to invert the eyelets of one series

relatively to those of the other because the hopper is so constructed that only those eyelets that are correctly positioned on the bottom of the hopper for both series will pass out. This constitutes one of the novel features of this invention. Another novel feature is that a single rotary feeder supplies both series of eyelets through separate ports leading to the raceways, the tufts of bristles, or whatever is provided to act on the eyelets, urging the eyelets of one series through the port 28 and then urging the eyelets of the other series through the ports 26, and so on alternately.

The rotary feeder is carried by a spindle 31 journaled in the bottom of the hopper as shown by Fig. 3, said spindle having a head at its lower end. A shaft 32 is journaled in the bracket 29 in coaxial relation to the spindle 31 and has a head 33 at its upper end. The heads 31 and 33 are provided with loosely fitting cooperative tongue-and-groove formations which form a clutch or coupling to transmit rotation from the shaft to the spindle, the tongue 34, in the form shown, being formed on the head of the spindle and the groove being formed in the head of the driving shaft.

The bottom piece 19 by which the raceways and hopper are rigidly connected to form a unit is preferably detachable from the swinging frame 21 and fastened to the latter by a screw 70 and dowels so that various raceway units may be used to replace one another according to the size and style 100 of eyelets or other fasteners required. The couplings 34 of the several units readily go into the coupling 33 and the loose play afforded by them takes care of slight errors in machining so that they will not cause 105 binding.

A sun gear 35 is fixed to the shaft 32, and above that a pulley 36 is arranged on the shaft but is not fastened to the shaft, the purpose being to utilize the shaft as a 110 mounting for the pulley and to permit the latter to rotate at high speed while the shaft is rotating at low speed. The hub of the pulley extends through a sun gear 37, which constitutes a journal therefor, said gear having a hub extending through a portion of the frame 21 and being fixed relatively to the frame by any preferred means such as a set screw 38. The pulley carrier planet gears 39 and 40 connected by a spindle 41, 115 the gear 39 being arranged to roll around the gear 37 in meshed relation thereto and the gear 40 being arranged to roll around the gear 35 in meshed relation. The rotation imparted to the shaft 32 depends upon 120 the difference in diameter as between the gears 35 and 37, with a corresponding difference in diameter between gears 39 and 40. If the maximum reduction is desired 125 a single tooth may represent the difference 130

between the gears 35 and 37, and such is the case in the illustrated construction. The gear 35 has one tooth more than the gear 37, and accordingly the gear 39 has one tooth more than the gear 40. This arrangement of gearing is such that although the pulley 36 may rotate at a comparatively high speed, say 300 R. P. M., the gearing will reduce the speed so that the shaft 32 will turn 10 at the rate of say 15 or 20 R. P. M.

A belt running over idle pulleys 43 transmits rotation to the pulley 36 from a driving pulley 44. This driving pulley is loosely mounted on the cam shaft 25 which usually 15 runs at a speed somewhere between 250 to 500 or even 600 R. P. M. Figs. 1 and 6 illustrate the well-known form of disconnectible clutch for driving the shaft 25, and the mechanism now about to be described is 20 such that it may be used to drive the belt 42 continuously or, when preferred, only when the shaft 25 is rotating.

The disconnectible clutch for operating the machine is provided with a pulley 45 which 25 may be regarded as a continuously rotating member. The hub of this pulley is mounted on the shaft 25 so as to turn without necessarily transmitting rotation to the shaft, the pulley being held against endshake by a collar 46 on one side and by a collar 47 on the opposite side. The collar 46 is fastened directly to the shaft but the collar 47 is fitted 30 to the driven member 48 of the clutch. This member 48 is keyed, pinned, or otherwise 35 fixed to the shaft, and is provided with a longitudinally movable bolt 49. One end of the bolt is adapted to engage a stud 50 projecting from the hub of the pulley 45 but is adapted to be retracted to clear the stud 40 and thereby disconnect the pulley from the driven member 48. A compression spring 51 normally shoots the belt into driving position. A collar 52 surrounds the shaft 25 and is adapted to slide axially, the bolt being 45 fixed to the collar so as to be retracted and controlled thereby. A flange 53 embodying a wedge formation is formed on the collar for cooperation with a controlling pin 54. For present purposes it will be 50 sufficient to state that the pin 54 is arranged to slide lengthwise in fixed bearings and is normally urged by a spring in the direction indicated by an arrow but may be retracted by a treadle or any other desired operating 55 means for the purpose of tripping the clutch. This construction is more fully illustrated in United States Letters Patent 1,351,138 granted August 31, 1920, on application of R. B. Smith.

60 The construction shown at the right of Fig. 6 provides for connecting the pulley 44 directly to the pulley 45 or to the shaft 25, as desired. The pulley 44 is arranged to rotate on an extension 55 of the shaft 25 65 when the shaft is at rest. For this purpose

the pulley is provided with a stud 56 adapted to engage a stud 57 carried by the continuously rotating pulley 45. To establish direct driving connection between the two pulleys the pulley 44 may be shifted to the left, but when it is shifted to the right the stud 56 clears the stud 57 and thus breaks such connection. The right-hand end of the pulley 44 is provided with a stud 58 arranged to establish driving connection 70 with a pin 59 projecting from a disk 60 fastened to the shaft 25, 55. The pulley 44 thus constitutes the driven member of a double clutch to the end that the feeder 20 may be driven continuously by the pulley 80 45 regardless of periods of inactivity of the shaft 25, or it may be uncoupled from the pulley 45 and coupled to the shaft 25 so as to be driven only during such periods of activity. 85

A hand lever 61 is provided for shifting the pulley 44 laterally from one operative position to the other. This lever is attached to a fixture 62 by a pivot member 63 and is provided with a finger 64 arranged in a peripheral groove 65 formed in the pulley. A spring-pressed follower 66 cooperates with a double beveled boss 67 on the finger 64 to maintain the pulley 44 in one clutched position or the other as the case may be. 90 This follower is arranged in a socket drilled in the fixture 62. 95

To charge the raceways with eyelets the pulley 44 may be clutched to the continuously rotating pulley 45, and when the raceways have been sufficiently charged the handle 61 may be moved to unclutch the pulley 44 from the pulley 45 so that the belt 42 will be driven only when the machine is operating to insert eyelets in the work. 100 If, at any time thereafter, the operative observes that the eyelets are not being fed into the raceways sufficient to maintain full charging he may again shift the pulley 44 into clutched relation with the continuously 105 driven pulley 45, and this would soon charge the raceways to full capacity so that it would be advisable again to return the pulley 44 to the clutched relation represented by Fig. 6. This shifting of the pulley 44 110 may be repeated as often as necessary to maintain the full or desired quantity of eyelets in the raceway. 115

Having thus described my invention, what I claim as new and desire to secure by Letters Patent of the United States is:

1. Fastener-supplying means comprising a hopper for containing a mass of indiscriminately arranged fasteners, and two raceways connected to said hopper and each arranged to conduct fasteners from the bottom thereof, said hopper being formed to deliver to one of said raceways only those fasteners that stand on the bottom in one predetermined position and to deliver to 120 125 130

the other raceway only those fasteners that stand on the bottom in another predetermined position.

2. Fastener-supplying means comprising a hopper for containing a mass of indiscriminately arranged fasteners, and a plurality of raceways, each arranged to conduct fasteners from the bottom of said hopper, the hopper having an outlet port communicating with one of said raceways and formed to emit only those fasteners that stand on the bottom in one predetermined position, the hopper also having an outlet port communicating with another raceway and formed to emit only those fasteners that stand on the bottom in another predetermined position.

3. Fastener-supplying means comprising a hopper for containing a mass of indiscriminately arranged fasteners, said hopper having an outlet port formed to emit only those fasteners that stand in one predetermined position on the bottom of the hopper, and having another outlet port formed to emit only those fasteners that stand on said bottom in a position the reverse of that first specified, and raceways arranged to receive the emitted fasteners from said ports.

4. Fastener-supplying means comprising a hopper for containing a mass of indiscriminately arranged fasteners, said hopper having an outlet port in a side wall formed to emit only those fasteners that stand in one predetermined position, and having a separate outlet port partly in a side wall and partly in the bottom formed to emit only those fasteners that stand in another predetermined position, and means arranged to receive the fasteners from said ports.

5. A hopper for supplying fasteners from a mass of indiscriminately arranged fasteners, having separate outlet ports one of which is formed to emit only those fasteners that stand in one predetermined position and another of which is formed to emit only those that stand in another predetermined position.

6. A hopper for supplying fasteners from a mass of indiscriminately arranged fasteners, having a stationary flat bottom, a stationary upstanding wall, an outlet port in said wall formed to emit only those fasteners that stand in one predetermined position on said bottom, and an outlet comprising a channel in said bottom and a port in said wall formed to emit only those fasteners that stand in another predetermined position.

7. A hopper for supplying eyelets from a mass of indiscriminately arranged eyelets, having a stationary flat bottom, a stationary upstanding wall, an outlet port in said wall formed to emit only those eyelets whose barrels extend upwardly from their flanged ends, and an outlet comprising a port in

said wall and a channel in said bottom leading past said port, said channel being adapted to receive the barrels only of those eyelets whose barrels extend downwardly from their flanged ends.

8. The combination with duplex eyelet-inserting mechanism, of a hopper for containing a mass of indiscriminately arranged eyelets, and two raceways arranged to conduct eyelets in two series from said hopper to said inserting mechanism, said hopper having an outlet port formed to supply to one of said raceways only those eyelets that stand flange end up, and having another outlet port formed to supply to the other raceway only those eyelets that stand flange end down.

9. The combination with mechanism for inserting simultaneously a plurality of fasteners in two relatively opposed or reverse positions, of a hopper for supplying such fasteners from a mass of indiscriminately arranged fasteners, said hopper having outlet ports of two kinds to emit only those fasteners that stand in two relatively opposed or reverse positions, and raceways arranged to conduct the fasteners from said ports to said inserting mechanism so as to preserve the opposed relation of the fasteners established at the ports.

10. The combination with mechanism arranged to insert one eyelet flange up and another eyelet flange down, of an eyelet-hopper having an outlet port arranged to emit eyelets flange up and another port arranged to emit eyelets flange down, and raceways arranged to conduct eyelets from said ports respectively to said inserting mechanism.

11. The combination with mechanism arranged to insert two fasteners in relatively reverse positions, a hopper constructed and arranged to emit from a mass of indiscriminately arranged fasteners a series of fasteners standing in one of said positions on the bottom of the hopper and a series standing in the other one of said positions on said bottom, and raceways arranged to conduct the fasteners so emitted from the hopper to said inserting mechanism.

12. The combination with fastener-inserting mechanism including a high-speed operating shaft, of fastener supplying mechanism comprising a reciprocatory carrier, a raceway and hopper carried by said carrier, a rotary device arranged to feed fasteners from said hopper to said raceway, and transmission means arranged to be operated by said shaft to drive said feeding device and including planetary speed-reducing gearing carried by said carrier.

13. The combination with fastener-inserting mechanism including a high-speed operating shaft, of fastener-supplying mechanism comprising an oscillatory raceway, a

- hopper for fasteners, a rotary device arranged to feed fasteners from said hopper to said raceway, and transmission means arranged to be operated by said shaft to drive 5 said feeding device and including planetary gearing arranged in coaxial relation to the axis about which said raceway oscillates and organized to reduce the speed of transmission.
- 10 14. The combination with fastener-inserting mechanism including a high-speed operating shaft, of fastener-supplying mechanism comprising a hopper for fasteners, a raceway arranged to conduct fasteners from 15 the hopper to said inserting mechanism, a rotary device arranged to feed fasteners from said hopper to said raceway, a rotary sun-gear and a non-rotary sun-gear of unequal diameter arranged in coaxial relation 20 to the axis of said feeding device, a rotary carrier in coaxial relation to said axis, means arranged to transmit rotation from said shaft to said rotary carrier, a planetary unit carried by said rotary carrier and including planet-gears of unequal diameter 25 arranged to mesh respectively with said sun-gears, and means arranged to transmit rotation from said rotary sun-gear to said fastener-feeding device.
- 30 15. The combination with an organization including fastener-inserting mechanism, a rotary shaft for operating said mechanism,

and a disconnectible clutch arranged on said shaft for driving the latter, of a raceway arranged to supply fasteners to said inserting 35 mechanism, mechanism arranged to charge said raceway with fasteners, and adjustable transmission means arranged to be coupled alternatively with the driving member of said clutch and with said shaft to operate 40 said charging mechanism continuously or periodically as the case may be.

16. The combination with an organization including fastener-inserting mechanism, a rotary shaft for operating said mechanism, and a disconnectible main clutch arranged on said shaft for driving the latter, of means including a fastener-feeding device for supplying fasteners to said inserting mechanism, and transmission means arranged to 50 operate said fastener-feeding device, said transmission means including clutch elements carried respectively by the driving member of said main clutch and by said shaft, and a shiftable clutch member arranged to be coupled alternatively with said driving member and with said shaft by said clutch elements to operate said fastener-feeding device continuously or periodically, as 55 the case may be.

In testimony whereof I have signed my name to this specification.

PERLEY R. GLASS.
